US00D963239S

(12) **United States Design Patent** (10) Patent No.: **US D963,239 S**
Powell et al. (45) Date of Patent: ** Sep. 6, 2022

(54) **AEROSOL GENERATOR**

- (71) Applicant: **Nicoventures Trading Limited**, London (GB)
- (72) Inventors: **David Hillary Powell**, London (GB); **Matthew Peter Tidnam**, London (GB); **Alex Pearce**, London (GB); **Caroline Jeanne Victoire Jacob**, London (GB)
- (73) Assignee: **Nicoventures Trading Limited**, London (GB)
- (**) Term: **15 Years**
- (21) Appl. No.: **29/778,261**
- (22) Filed: **Apr. 12, 2021**

Related U.S. Application Data

- (62) Division of application No. 29/705,487, filed on Sep. 12, 2019.
